[57] CLAIM

The ornamental design for a television set, as shown and described.

DESCRIPTION

FIG. 1 is a top plan view of a television set showing my new design;

FIG. 2 is a right side elevational view thereof, the left side elevational view being a mirror image thereof;

FIG. 3 is a front elevational view thereof;

FIG. 4 is a rear elevational view thereof; and,

FIG. 5 is a bottom plan view thereof.

The chord is shown broken away for ease of illustration.
